United States Patent Office.

ARCHIBALD HUTTON, OF ST. LOUIS, MISSOURI.

Letters Patent No. 71,016, dated November 19, 1867.

IMPROVEMENT IN VALVES FOR STEAM ENGINES.

The Schedule referred to in these Letters Patent and making part of the same.

TO ALL WHOM IT MAY CONCERN:

Be it known that I, ARCHIBALD HUTTON, of St. Louis, in the county of St. Louis, and State of Missouri, have made certain new and useful Improvements in Condensing Attachment for High-Pressure Steam Engines; and I do hereby declare that the following is a full and clear description thereof, reference being had to the accompanying drawings, and to letters of reference marked thereon.

The nature of this invention consists in arranging the slide-valve on an auxiliary valve of a steam engine in such a manner as to permit the first part and largest volume of the exhaust steam to escape into the open atmosphere, through an escape-chimney, as is usual with high-pressure engines; then the remainder of the exhaust steam is, by the peculiar construction of the valve and exhaust-passages, to be turned aside into the condenser, and by this means a tolerably perfect vacuum may be produced in the cylinder, and at a very trifling expense.

In adapting these improvements to high-pressure engines now in use, it will be necessary to apply an auxiliary valve, in addition to the ordinary valves at present in use, but when a new engine is to be built, one single valve may be constructed so as to be able to act as steam, exhaust, and condensing-valve. In allowing the largest volume of steam to escape through the exhaust-chimney into the open air, it is obvious that but a small volume of steam will remain in the cylinder to be condensed, and hence the amount of cold water used in the condenser will be very small, and this fact alone will so cheapen the operation of a condensing engine as to permit its use in municipalities where the cost of water is an important item of expense.

To enable those skilled in the art to make and use my improved condensing attachment, I will proceed to describe its construction and operation.

Figure 1 of the drawings is a longitudinal sectional elevation of the improved condensing attachment, showing the auxiliary valve arrangement, taken on line $x-y$.

Figure 2 is a transverse sectional elevation of same, taken on line x^1-y^1 of fig. 1.

Figure 3 is a sectional plan of the exhaust-passages leading to the condenser, taken on line x^2-y^2 of figs. 1 and 2.

If this condensing attachment is to be applied to an old high-pressure engine, the valve A will be an auxiliary valve, used in combination with the ordinary valve of the engine; but if the attachment is to be applied to a new engine, the said valve A may be so constructed and operated as to perform the entire office of steam, exhaust, and condenser-valve. In this case the valve-chest A' will become the steam-chest of the engine. The valve A has a central port, a , which, at the first moment of the exhaust, is to be arranged so as to cover the exhaust-port a^1 of the engine, and the port a^2 leading to the escape pipe, thus opening a direct passage for the exhaust steam to escape through the exhaust-chimney, (not shown.) At one, or at both ends of the valve A, are port openings, a^3 , which, by means of the proper cam motion, are to be made to uncover the exhaust-port a^1 the moment after the first and largest volume of steam shall have escaped up the chimney. When either of these port openings a^3 is over the port a^1 , it will open communication between the said port and the ports a^4 , at the ends of the said port a^1 , as is clearly shown in fig. 2, at the same time closing the port a^2 leading to the exhaust-chimney, and thereby opening communication between the cylinder and the condenser through the tortuous passages B, while closing that to the escape-chimney. By these arrangements it will readily be seen that as soon as the largest volume of the steam shall have escaped through the exhaust-chimney the remaining portion left in the cylinder will be turned aside into the condenser, through the passages B, and then condensed with a trifling expenditure of water.

I do not intend to confine myself to the precise form of valve herein described, well knowing that many variations in the form of said valves may be readily constructed by expert engineers; but it is hereby declared to be clearly within the scope of my invention to use any form of valve by means of which the exhaust steam from the cylinder of a steam engine may be allowed to escape up the exhaust-chimney, until the bulk of the steam shall have left the cylinder, and then the remainder turned aside into the condenser, and thereby a tolerably perfect vacuum created in the cylinder.

This device is equally applicable to engines which escape into the open atmosphere or into auxiliary cylinders.

Having described my invention, what I claim, is—

The valve A, when constructed with one or two port-openings, a^3 , and combined with the ports a^1 a^2 , and the condenser-passage B, as described and set forth.

ARCHIBALD HUTTON.
